UNITED STATES PATENT OFFICE.

ALEXANDER R. DEMPSTER, OF DES MOINES, IOWA, ASSIGNOR TO THE DEMPSTER MANUFACTURING COMPANY, OF SAME PLACE.

WINDMILL.

SPECIFICATION forming part of Letters Patent No. 651,544, dated June 12, 1900.

Application filed May 15, 1899. Serial No. 716,830. (No model.)

To all whom it may concern:

Be it known that I, ALEXANDER R. DEMPSTER, a citizen of the United States of America, and a resident of Des Moines, Polk county, Iowa, have invented certain new and useful Improvements in Windmills, of which the following is a specification.

The object of this invention is to provide improved means for balance-gearing and supporting a vaneless windmill and throwing the feathering wind-wheel into and out of the wind.

My invention consists in the construction, arrangement, and combination of elements hereinafter set forth, pointed out in my claims, and illustrated by the accompanying drawings, in which—

Figure 1 is an elevation of a portion of a windmill illustrating my improved construction. Fig. 2 is a vertical section of a portion of the devices shown in Fig. 1. Fig. 3 is a bottom plan of the cap and the upper individual of the nest of gears. Fig. 4 is a cross-section of the device, the cap and upper gear being removed. Fig. 5 is a plan of the ring employed to carry the cap and upper gear. Fig. 6 is an elevation of one of the sections of the cap. Fig. 7 is a detail vertical section illustrating the means employed to connect the cap and ring. Fig. 8 is a vertical section on the indicated line 8 of Fig. 6.

In the construction of the device as shown the numerals 10, 11, 12, and 13 designate the posts of a windmill-tower, constructed of angle-plates and connected and supported in any desired manner. A bowl-shaped bed-plate 14 is mounted between the posts of the tower and provided with integral radially-extending arms 15, 16, 17, and 18, turned downwardly at their extremities and slotted to receive bolts 19, 20, 21, and 22, which bolts traverse bolt-holes in the posts and are secured by nuts 23 on their outer ends impinging the outer faces of the posts. The upper edge or rim of the bowl-shaped bed-plate is horizontal, and an aperture 24 is formed in the center of the lower portion of the plate to receive a shaft 25, vertically positioned therein. The lower end of the shaft 25 is coupled to the upper end of a power-shaft 26, and said power-shaft may be geared in any de-

sired manner to a machine to be driven, the coupling 27 therefor being connected to the shaft 25 by a feather-key 28. An annular race or seat 29, inclined in cross-section, is formed in the upper edge of the rim of the bowl-shaped bed-plate 14 concentric with the center of the bowl, and a miter-gear 30 is mounted rigidly on the upper end of the shaft 25 within the bowl and below the horizontal plane of the race. A wear-plate 31 is mounted loosely around the shaft 25 between the lower face of the hub of the wheel 30 and the upper face of the lower portion of the bed-plate. An annular turn-table or ring 32 is provided of slightly-greater diameter than the race 29 and positioned immediately above the rim of the bowl-shaped bed-plate 14. The turn-table 32, Fig. 5, is provided with a series of studs or pivots 33—in this instance six in number—seated transversely of the rim thereof and projecting inwardly therefrom. Frustum-shaped rollers 34, 35, 36, 37, 38, and 39 are mounted loosely on the inwardly-projecting portions of the studs or pivots 33 and are arranged for travel on the rim of the bowl-shaped bed-plate and within the race 29. The studs or pivots 33 are spaced apart equal distances, and consequently the rollers, projecting below the lower edge of the rim of the turn-table, support the turn-table and balance it firmly for revolution. A hub 40 is located in the center of the turn-table 32 and integrally connected to the rim thereof by spokes 41, 42, 43, and 44. A shaft 45 is mounted diametrically of and entirely across the turn-table 32, and the ends thereof are secured against rotation in the rim between the rollers 34, 39 and 36, 37. Miter-gears 46, 47 are mounted loosely for revolution on the shaft 45 and mesh with and on diametrically-opposite points of the miter-gear 30. Studs, lugs, or projections 48, 49, and 50 are formed on and radiate from the outer face or periphery of the turn-table 32 at equal distances of separation. A cap 51, formed in two sections 51^a, 51^b of dome shape, is provided and positioned immediately above the bed-plate 14 and concentric with the axis of the shaft 25. The sections of the cap are formed with ribs or flanges 52, 53 on their plane margins and abutting each other, and said flanges are

connected by bolts 54, secured by nuts in a common manner. The rim portion of the cap 51 is formed with offsets, forming bosses or projections on the exterior and notches or 5 seats 55, 56, and 57 on the interior. The seats or notches of the cap are spaced apart equal distances and of such size and shape as to receive and engage snugly the lugs or projections 48, 49, and 50 on the periphery of the 10 turn-table 32. Thus the turn-table 32 is secured to and supports the cap 51. A hub is formed on and at the center and top of the cap, one-half of the hub being in each section, and is centrally bored to receive the 15 lower end portion of a sleeve 56, vertically positioned and extending upwardly from the cap. Set-screws 57 are mounted in the hub of the cap and impinge the periphery of the sleeve 56 at their inner ends. A socket is 20 formed in the center of the upper face of the hub 40 of the turn-table 32, and a plate 58 rests in said socket. A retaining-plate 59, formed with a central circular aperture, is mounted on and bolted to the top of the hub 40, with 25 its aperture immediately above the socket in said hub. A shaft 60 is mounted in the sleeve 56 and stepped on the plate 58, and the lower end of said shaft is retained against lateral movement by the plate 59. Oil may be placed 30 in the socket of the hub 40 to lubricate the lower end of the shaft 60 on the plate 58. A miter-gear 61 is mounted rigidly on the shaft 60 immediately above the plate 59 and meshes with and on diametrically-opposite points of 35 the gears 46 47. The lower end portion of the sleeve 56 is journaled in the center of a steady-bearing 62, also formed in sections and connected by bolts 63, provided with radial arms arranged and so shaped as to be secured 40 to the tower-posts above the arms of the bowl-shaped bed-plate. A collar 64 is mounted loosely on the sleeve 56 and is formed with an annular peripheral groove. A bracket 66 is mounted on the tower-post 13, and a link 45 67 is pivoted at its upper end on the bracket and depends therefrom. A lever 68 is fulcrumed at one end on the lower end of the link 67 and extends across the collar 64 and beyond the post 10. A strap is bolted to the 50 lever 68 in opposition to a flexed or offset portion of said lever, and pins 69 in the lever and strap (one only of which is shown) enter the annular peripheral groove in the collar 64. A platform 70 is mounted on and projects 55 outwardly from the tower-posts above the collar 64, and a rod 71 is fixed to and rises from the collar. The rod 71 is adapted to connect the collar 64 to lever mechanism of common form, whereby the feathering-blades of the 60 wind-wheel may be operated into or out of the wind. A draft rod or wire 72 is attached to and depends from the free end of the lever 68 and may be operated manually to pull the lever downwardly, depress the collar 64 and 65 rod 71, and throw the mill out of the wind. A draft-wire 73 is attached to the free end portion of the lever 68, extended over a sheave

74, beneath the platform 70, and depends from said sheave. The draft-wire 73 may be operated manually to elevate the lever, collar 64, 70 and rod 71 and throw the wind-wheel into the wind.

In practical use and operation the cap is carried by the ring or turn-table and the turn-table is carried by the rollers traveling in the 75 race 29. The sleeve is carried by the cap, and said sleeve carries the windmill-head. The bed-plate 14 supports the miter-gear 30, which meshes with and is driven by the miter-gears 46 47 and in turn drives the shaft 25, coupling 27, and shaft 26. The connection, by means of the feather-key 28, between the coupling 27 and shaft 25 permits the coupling and weight carried thereby to move downwardly without straining or pulling on the shaft 25. Therefore the bed-plate is relieved 80 of the weight of the coupling and shaft 26. The miter-gears 46 47 are carried by the turn-table, and the hub of said turn-table carries the shaft 60 and miter-wheel 61, said latter 90 wheel meshing with and driving the gears 46 47. Thus the mill-head is free to revolve under the influence of shifting air-currents on the bed-plate 14 by means of the frustum-shaped rollers traveling in the race 29 95 without in any manner altering the operation of the miter-gears, the power communicated through said gears being constant and unvarying, save and except as the speed of the wind-wheel varies under the changing forces 100 of the air-currents.

By forming the cap in sections I am enabled to remove one section thereof and have access to the nest of gears, race, and rollers.

By the use of the lever 68, fulcrumed at 105 one end and controlled by two draft wires or rods, I am enabled to control and adjust the feathering-blades of the wind-wheel positively and conveniently.

I claim as my invention—

1. The combination of the bed-plate formed with an annular race, a turn-table, rollers on said turn-table and mounted for travel in the race, a cap carried by said turn-table and non-contacting with the rollers, the sleeve carried by the cap and arranged for attachment to a windmill-head, a shaft mounted for rotation in the bed-plate, a miter-gear on said shaft above the bed-plate, miter-gears on the turn-table meshing with the gear on the shaft, a shaft stepped on the turn-table, a miter-gear on the latter shaft and meshing with the gears on the turn-table, which latter shaft is adapted for gearing with a wind-wheel, and means for connecting the first shaft to a machine to be driven.

2. In a windmill, the bed-plate formed with a race, the rollers arranged for travel in the race, the ring pivotally connected with and carried by said rollers, the cap mounted on the ring above and spaced apart from the rollers and means for connecting said cap to a windmill-head.

3. In a windmill, the combination of the

bed-plate formed with a race, the turn-table mounted above the bed-plate, the pivots mounted on and projecting inwardly from the rim of said turn-table, the frustum-shaped rollers mounted for revolution on said pivots and arranged for travel in the race of the bed-plate, the radial projections on the rim of the turn-table, the cap formed with seats or notches in its rim arranged and so shaped as to receive the radial projections on the turn-table, which cap is above and spaced apart from the rollers, and means for connecting the cap to a windmill-head.

4. The bed-plate formed with an annular race, the annular turn-table mounted above the bed-plate, the pivots mounted on and projecting inwardly from the turn-table, the frustum-shaped rollers mounted loosely on said pivots and resting on the bed-plate with 15 in the race, the radial projections on the turn-table, the cap formed in sections bolted together and provided with seats arranged and so shaped as to receive the projections of the turn-table, which cap is above and spaced 20 apart from the rollers and wholly supported by the turn-table, and means for connecting said cap to a windmill-head.

5. The combination of the tower-posts, the bed-plate, the arms on said bed-plate, which 25 arms are turned downwardly at their extremities and slotted for attachment to said posts, the turn-table positioned above and parallel with the upper edge of the bed-plate, the pivots on said turn-table, the rollers on 30 said pivots resting on the bed-plate, the cap fixed to and wholly carried by the turn-table and above and spaced apart from the rollers, the sleeve fixed to and rising from said cap, the miter-wheel in the bed-plate, the 35 shaft fixed to and depending from the miter-wheel through said bed-plate, the shaft traversing the turn-table, the miter-wheels thereon and meshing with the first miter-wheel, the shaft stepped on the turn-table and ris-

ing through said sleeve, the miter-wheel on 45 the latter shaft and meshing with the miter-wheels on the turn-table and the steadyng-bearing surrounding the sleeve and attached to the posts.

6. The bed-plate formed with an annular race, the annular turn-table mounted above the bed-plate, the pivots mounted on and projecting inwardly from the turn-table, the frustum-shaped rollers mounted loosely on 50 said pivots and arranged for travel on the bed-plate and within the race thereof, the shaft 25 vertically traversing the bed-plate, the miter-gear 30 rigidly mounted on the upper end of said shaft and stepped on the bed-plate, a hub 40 centrally of the turn-table and 55 rigidly connected to the rim thereof, a shaft 45 mounted diametrically of and entirely across the turn-table and secured against rotation by its ends fixed in the rim of said turn-table, miter-gears 46, 47 mounted loosely 60 on the shaft 45 on opposite sides of the hub 40 and meshing, at diametrically - opposite points, with the miter-gear 30, the shaft 60 stepped in the hub 40 and supported thereby, the miter-gear 61 mounted rigidly on the 65 shaft 60 and meshing, at diametrically-opposite points, with the miter-gears 46, 47, the radial projections on the turn-table, the cap formed of sections bolted together and provided with seats arranged and so shaped as 70 to receive the projections of the turn-table, which cap is above and spaced apart from the rollers and wholly supported by the turn-table, and is loosely traversed by the shaft 60, and means for connecting said cap to a wind- 75 mill-head.

Signed by me at Des Moines, Iowa, this 3d day of April, 1899.

ALEXANDER R. DEMPSTER.
